CLAIM

The ornamental design for a facial toning machine, as shown and described.

DESCRIPTION

FIG. 1 is an isometric view of a facial toning machine showing my new design from the top, front and right side;

FIG. 2 is an isometric view thereof, seen from the bottom, rear and left sides;

FIG. 3 is an isometric view shown with the cover element in a raised position; and,

FIG. 4 is a top plan view of the machine as shown in FIG. 3.
